TOOL FOR REMOVING RIDGES

Lawrence O. Beard, Lancaster, Pa.

Application July 29, 1932, Serial No. 625,917

3 Claims. (Cl. 77—2)

This invention relates to tools for removing ridges from the walls of cylinders. It is well known that under constant reciprocatory piston movement the walls of an internal combustion engine gradually become worn, leaving an objectionable ridge at the top of the cylinder which interferes with proper piston action when new piston rings are installed.

The general object of the present invention is to provide a simple form of cutting tool which will effectively remove the objectionable ridge just referred to.

Another object of the invention is to provide means for proper guiding or piloting the cutter blades during operation of the tool.

Other and more specific objects and advantages of the invention will be apparent as the specification is considered in connection with the accompanying drawing, in which:

Figure 1 is a plan view of the improved tool in operative position on a cylinder block;

Figure 2 is a section on the line 2—2 of Figure 1;

Figure 3 is a section on the line 3—3 of Figure 4;

Figure 4 is a bottom plan view of the cutter head shown in Figure 3;

Figure 5 is a side view of the rotary expansion plug for expanding the cutter blades; and

Figures 6 and 7 are perspective views showing the rear and front ends of the cutting blades respectively.

Referring more particularly to the drawing T denotes the tool as a whole including a cutter head 1, having a depending cylindrical body portion 2, adapted to be loosely received within the cylinder bore 3 of an internal combustion engine, not shown. Arms or lugs 4, preferably integrally formed, extending radially from the top of the body 2, seat upon the cylinder block 5 and support the tool in place. A centrally disposed upstanding projection 6 formed on the cutter head is provided with a threaded bore 7 communicating with an axially aligned larger bore 8, extending to and through the bottom of body 2.

Cutter blades 9 are slidably mounted in open ended radial slots 10 formed in the cutter head body 2 and extending from the bore 8 to and through the outer periphery of the said body. A plate 11 secured to the bottom of the cutter head by screws 12, holds the blades in place. Expansion is effected by means of a beveled rotary expansion plug 13 the threaded stem 14 of which is mounted in opening 7 previously referred to.

When the stem 14 of plug 13 is rotated in an appropriate direction, by a standard wrench or other suitable tool, not shown, the bevel face 15 of the body portion 25 of the plug will be moved downwardly against the beveled inner face 16 of blades 9 thus forcing the blades outwardly into contact with the wall of cylinder bore 3. The tool as a whole is then turned approximately one revolution by means of a suitable tool, not shown, applied to the squared end 17 of projection 6, and this operation is repeated as often as necessary to remove the ridge 18, it being understood that the cutter blades will be slightly advanced or expanded after each revolution of the cutter head by rotating stem 14. As previously stated a standard wrench can be used to rotate the expansion plug, the upper end of stem 14 thereof being provided with a tool engaging squared end 19 for this purpose. If desirable rotation of the tool T and feeding of the cutter blades can be simultaneously effected by the employment of two wrenches for turning the cutter head and expansion plug respectively. Of course this would necessitate the workman using both hands, one for each wrench. The cooperating beveled faces 15 and 16 of the expansion plug and cutters are preferably formed of an angle of approximately forty five degrees to the axis of the cutter head but any angularity may be employed provided the angle is the same on each face.

The outer end face 20 of cutter blade 9 is ground on a slightly greater radius than the diameter of the cylinder to be ground so that a bearing will be had at both the front and rear pilot edges 21 and 22 respectively. This face 20 is also formed with a substantially rectangular cut out or recessed portion 21' in the upper forward edge thereof, the sharp cutting edge 22' of which is in the same vertical plane as the front pilot edge 21, and in effect a continuation of such cutting edge. In order to provide a relief for the cutting edge and to prevent scoring or scratching of the cylinder wall, the rear pilot edge of the blade is slightly rounded or honed off. It will thus be seen that the blades 9 are guided or piloted by the pilot edges 21 and 22 both back of and below the cut out portion 21', thus effectually eliminating chattering and insuring uniformity and smoothness of operation.

By forming the lugs or arms 4 integral with the body of the cutter head it is possible to have the cutters square with the cylinder bore. When the tool is dropped in place, the cutting portions 21' of the blades will extend slightly above the bottom face of the lugs or arms 4 and conse-

quently above the top of the cylinder thus insuring engagement of the said cutting portions with the entire surface of the ridge 18 to be removed.

Having thus described my invention:

5 What I claim is:

1. A tool for removing ridges from the top of a cylinder comprising a cylindrical cutter head body portion, three symmetrically arranged lugs extending radially from said body adapted to seat 10 said body upon the cylinder block and suspend same into said cylinder, said body having a central bore and open ended radial slots of substantial width communicating with said bore; a hollow internally threaded extension on the top 15 of said body communicating with said bore, blades of substantial thickness adjustably mounted in said slots and formed with inner beveled ends said blades having means on one end for relieving the cutting edge of said blades, an expansion plug having a stem threadedly mounted in said threaded extension and a beveled head portion freely engaging the beveled ends of the blades, said stem and said extension have tool 20 engaging extremities for the application of a wrench or other tool.
2. A tool for removing ridges from the top of a cylinder comprising a bored cylindrical cutter head body portion, three symmetrically arranged lugs extending radially from said body portion for supporting said cutter head upon a cylinder block, said body having a plurality of wide radial slots communicating with the bore of the cutter head, a hollow integral extension on 25

said cutter head, heavy blades of substantial thickness adjustably mounted in said slots, said blades having cut out portions in one end for relieving the cutting edge of said blades, a headed expansion plug having its stem rotatably mounted in said extension and engaging with its free head portion said blades, wrench engaging means on the stem of said expansion plug and said extension for selective rotation of said cutter head and said plug, cutting portions on said blades 10 extending above the top of the cylinder and above the plane of the bottom face of said lugs.

3. A tool for removing ridges from the top of a cylinder comprising a bored slotted cutter head, lugs on said head adapted to seat on the top of a cylinder block for rotatably supporting said head upon the block and suspend same into the cylinder, a hollow extension on the cutter head, heavy cutter blades in said slots, means rotatably mounted at one end in said extension engaging 15 with its free end, said blades for moving the same outwardly in said slots, said extension and said means having exterior wrench engaging surfaces, said blades having substantially rectangular cut out portions in an upper corner 20 thereof for forming the relief for the cutting edge of said blades, and the outer end faces of said blades being ground on a radius slightly greater than the diameter of the cylinder to be serviced thus forming pilot edges or bearing surfaces below and behind said cut out portions.
